[57] CLAIM

The ornamental design for a luggage case, substantially as shown and described.

DESCRIPTION

FIG. 1 is a side elevational view of a luggage case showing my new design, the hardware shown in dotted lines being for illustrative purposes only and not a part of the design;

FIG. 2 is an opposite side elevational view thereof;

FIG. 3 is a top plan view thereof;

FIG. 4 is a bottom plan view thereof;

FIG. 5 is an end elevational view thereof;

FIG. 6 is an opposite end elevational view thereof; and

FIG. 7 is a perspective view thereof.

FIG. 1

FIG. 2

FIG. 3

FIG. 4

FIG. 5
